UNITED STATES PATENT OFFICE.

ROBERT L. LYONS, OF WALTHAM, MASSACHUSETTS, ASSIGNEE TO THE FREDERICK OSANN COMPANY, OF NEW YORK, N. Y., A CORPORATION OF NEW YORK.

SEWING-MACHINE HAVING THREAD-CUTTING DEVICE.

1,272,066.

Specification of Letters Patent.

Patented July 9, 1918.

Application filed May 18, 1914. Serial No. 839,189.

To all whom it may concern:

Be it known that I, ROBERT L. LYONS, a citizen of the United States, residing at Waltham, in the county of Middlesex and State of Massachusetts, have invented certain new and useful Improvements in Sewing-Machines Having Thread-Cutting Devices, of which the following is a specification, reference being had to the accompanying drawings, forming part thereof.

This invention relates to improvements in single thread sewing machines in which the thread at the completion of a stitch extends from said stitch down and around the looper and from said looper to and through said stitch to the needle.

The object of the invention is to so construct a single thread sewing machine in which the sewing thread is sustained as a loop extending from the work around the looper that a cutting implement may be brought into operation or actuated to cut the arm of said thread loop which extends from the stitches to the looper.

Another object of the invention is to provide a novel thread cutting mechanism for single thread sewing machines.

Other objects of the invention will appear from the following description.

The invention consists in cutting a loop of the sewing thread while said loop is sustained by the looper.

The invention also consists in such other novel features of construction and combination of parts as shall hereinafter be more fully described and pointed out in the claim.

Figure 1 represents a side view of portions of a sewing machine illustrating the new improvement.

Fig. 2, represents a bottom plan view of portions of the same.

Fig. 3, represents a plan view of the cam for effecting the movement of the work relative to the stitch forming devices, and also showing means carried by said cam member through the action of which the thread cutter shifter or actuator may be operated in one direction.

Fig. 4, represents an edge view of a thread cutter device of the preferred form.

Fig. 5, represents a sectional view as taken on line 5—5 Fig. 1 showing the work at the completion of a series of stitches, the thread *a—b* extending as a loop from the last stitch around the looper and thence through the

work (arm *b* of said thread) to the needle, also showing one member of the thread cutting mechanism introduced between said arms *a—b* of the thread loop and with the thread cutter in position to act to cut the arm *a* upon a subsequent movement of said thread cutter.

Fig. 6, represents an enlarged diagrammatic sectional view of the thread loop and the cutting implement as taken on line 7—7 Fig. 5.

Fig. 7, represents an enlarged diagrammatic view of some of the parts shown in Fig. 5 but more clearly showing the location of the last stitch and the needle thread (arm *b*) extending through said stitch.

Similar characters of reference designate corresponding parts throughout.

The machine shown in the drawings is particularly adapted for the sewing of a group of stitches to attach a tag or ticket *T* to a piece of material *M*, but it is not my intention thereby to limit this invention to that class of machines. It is however my intention to limit my invention to a machine in which provision is made to effect in some manner a relative movement between the work and the stitch forming devices. It being understood that said relative movement between the work may be vibratory for a distance of one or more stitches or continuous in one direction for a series of stitches and that said relative movement between the work and the stitch forming devices is not limited to the movement of the work.

As shown in the drawings 5 is the bed plate of the machine having the standard 6 furnished with the arm 7 having the head 8 in which is operatively mounted the needle bar 9 carrying the needle 10 which co-operates with the looper 11 at the under side of the bed plate 5 to form chain stitches, so called. Provision of any ordinary means being made to effect the operation of said needle and said looper of which means the usual shaft 12 having the gear 13 preferably forms part.

At the under side of the bed plate 5 is rotatably mounted the cam disk 14 having the usual pinion which is driven by the gear 13 of shaft 12, in the usual manner to effect the rotation of said cam disk 14 during the operation of the stitch forming devices. This cam disk 14 has the cam path 16 which may or may not have the dwells 17, 17 and 110

said cam path 16 is shaped to effect the back and forth movement of the follower 18 engaged in said cam path and connected in any usual manner to the work holder 19 slidably mounted at the upper edge of bed plate 5. This work holder 19 has the cloth plate 20 and the presser foot 21 between which a piece of material M and a tag T, superposed on said material may be engaged and carried.

Adjustably mounted on said cam disk 14 are the cam members 22, 22 which when cam disk 14 rotates, act against the bevel end 23 of the plate 24 which is pivotally mounted and bears against the bent end 25 of lever 26 which lever end 25 is held in contact with pivoted plate 24 by spring 27. At its outer end lever 26 is pivotally connected with the slide 28 which is received in a guide of bed plate 5 and has the comparatively narrow shank 29 furnished with the loop spreader member 30 having the thread cutter 31.

Preparatory to the operation of this machine material M and a tag T are placed between the members 20 and 21 of the work holder or work feeding device 19. The machine is then operated and the work T, M, is fed or vibrated laterally with respect to the needle 10 and looper 11 while these stitch forming devices are operated to effect the formation of securing stitches through said work. The feeding or vibrating movement of the work is accomplished, in the construction referred to herein, by or through the rotation of cam disk 14 and its follower 18 connected with said work holder 19 while the cam groove 16 of said cam disk is acting on said follower.

Preferably the cam members 22, 22 are so mounted on the cam disk 14 relative to the cam path 16 and to the bevel end 23 of pivoted plate 24 that after the formation of a predetermined number of stitches one of said cam members 22 acts against said bevel end 23 of plate 24 and through the swinging of said plate effects the swinging of lever 26 to project the slide 28 forward during the upward movement of the needle in completing the next stitch so that the member 30 of the slide 28 passes forward through the arms *a*, *b* of the thread loop while said loop is sustained by the looper 11 and is under some slight tension. The actuating contact between the members 22

and the bevel end 23 of plate 24 is of very slight duration so that almost immediately after the member 30 of slide 28 passes forward through the thread loop *a*, *b* and reaches the position shown in Fig. 6 relative to the arms *a*, *b* of said loop, the end of member 22 clears the bevel end 23 of plate 24 and, hence, spring 27 is permitted to act to retract lever 26 and its slide 28 whereby cutter blade or member 31 acts to cut arm *a* of the thread loop close to the last stitch and any drawing action of said blade 31 on the arm *a* of the loop tends to draw tighter said stitches. This manner of cutting the thread loop leaves a comparatively long end of thread extending from the eye of the needle.

I understand that it is old in the art to provide, in a two thread machine, a thread cutting finger or member onto which a thread loop is cast from the shuttle as a preliminary step in a thread cutting operation and it is not my intention to claim at this time such device or any thread cutting device operating in combination with a two thread shuttle machine. I believe it to be new however to effect the cutting of a thread loop, in a single thread sewing machine, by the use of a thread cutting mechanism furnished with a member which is introduced into said thread loop and cooperates with a cutting device to cut one arm of said thread loop while said loop is still sustained by the looper, and it is my desire to claim such means broadly.

Having thus described my invention I claim as new and desire to secure by Letters Patent.

A single thread sewing machine comprising in combination, a needle and a looper, operating means therefor, a work holder, means for effecting relative movement between said work holder and said needle, a cutter member slidably mounted and having a loop engaging member and a blade having its edge positioned to act in the retractive movement of said cutter member, means to project said cutter member to introduce its loop engaging member into a loop of thread sustained by said looper, and spring means to retract said cutter member to cut said loop.

ROBERT L. LYONS.
